UNITED STATES PATENT OFFICE

HERBERT DREWS, OF DANVILLE, ILLINOIS, ASSIGNOR TO W. U. KOONS FURNACE COMPANY, OF DANVILLE, ILLINOIS

GRATE-SHAKING DEVICE

Application filed November 4, 1929. Serial No. 404,717.

This invention relates to new and useful improvements in furnace construction and which embodies among other characteristics a grate arrangement permitting the ashes and 5 clinkers to be most effectively removed without undue disturbance of the fire bed.

Another object of the invention consists in the provision and arrangement of a form of grate to be oscillated beneath the fire bed.

10 An additional object of the invention contemplates a central form of dumping grate to let the burned out middle of the fire bed to fall within the ash pit whereby the glowing coals adjacent the sides of the fire box 15 or fire brick lining therefor will be saved.

More specifically stated the different forms of grates are to be operated by a single control lever from a given position.

With the above and other objects in view, 20 the invention further consists of the following novel features and details of construction, to be hereinafter more fully described, illustrated in the accompanying drawings and pointed out in the appended claim.

25 In the drawings:

Figure 1 is a front elevation of the furnace partly broken away to illustrate the arrangement of the circular form of grate.

Figure 2 is a sectional view taken on line 30 2-2 of Figure 1.

Figure 3 is a sectional view taken on line 3-3 of Figure 2.

Figure 4 is a front elevation of the circular form of grate.

35 Figure 5 is a rear elevation of the circular form of grate.

Figure 6 is a perspective view of the control lever or grate shaker bar.

Figure 7 is a sectional view taken on line 40 7-7 of Figure 2 illustrating the arrangement of the gearing for the central forms of grate construction.

Figure 8 is a view similar to Figure 7 taken on line 8-8 of Figure 2 showing the connecting member for the central grate bars to preserve meshing engagement of said gears.

Referring to the drawings in detail wherever in like characters of reference denote corresponding parts, the reference character 10 indicates generally the casing of a furnace

having the major portion of its fire box compartment 11 lined with suitable heat resisting lining 12 in the nature of fire brick and the like.

An annular ring 13 having ears 14 depending from the under side thereof and secured to the casing 10 below the heat resisting lining or fire brick subdivides the lower portion of the furnace into a fire box and ash pit, the latter indicated as at 15. Arms 16, carried by and depending from the under sides of the ring 13 and inwardly offset in right-angularly disposed relation adjacent the ends thereof terminate to provide horizontally disposed arcuate-shaped supporting members 17.

The circular form of grate, referred to in the foregoing, and as indicated at 18, is provided with solid portions 19 at spaced intervals thereon tangentially thereof and disposed immediately above the supporting member 17. The under sides of the solid portions 19 are provided with grooves 20 disposed in such manner as to conveniently accommodate the adjacent portions of the supporting members 17 and to freely oscillate thereon. The circular type grate 18 is provided with a central opening 21, the purposes and advantages of which will be presently apparent.

Grate bars 22 and 23 respectively have the innermost spaced ends thereof journaled within apertured ears 24 depending from the ring 13 in the manner as best shown in Figures 2 and 3 of the drawings. Semi-circular grate members 25 and 26, carried upon the bars 22 and 23 respectively and having the flat sides thereof disposed in juxtaposition, ordinarily fill up the central opening 21 in the grate 18. Hook arms 27, carried upon the ring 13 and arranged in oppositely disposed relation and aligned with the apertured ears 24, journal the adjacent portions of the bars 22 and 23.

Segmental gears 28, carried by and simultaneously operated in conjunction with the grate bars 22 and 23 upon squared portions 29 thereon, are designed for meshing engagement in the manner shown in Figures 7 and 8 of the drawings whereby the semi-circular

grate sections 25 and 26 will be simultaneously tilted and righted. The teeth of the gears are constantly maintained in meshing engagement and held against spreading by a link member 30 having a bearing member 31 of cylindrical form upon one end telescopically associated with the grate bar 22 whereas a bearing member 32 of U-shape formation horizontally disposed upon its opposite end is designed to accommodate the remaining grate bar, namely 23, in the manner shown in Figure 8.

The grate shaker bar, indicated as at 33, is curved as at 34 upon its lowermost end and formed with the ball head 35. The ball head is mounted between the frame structure for the ash pit clean-out door and a centrally apertured cover plate 36. The aforementioned portion of the door frame is concaved, as at 37, to accommodate the adjacent rounded surface of the ball whereas its outer portion is projected for an appreciable distance through the centrally apertured plate 36. Long and short ears 38 and 39 respectively, inwardly projecting in spaced parallelism from that portion of the ball head 35 extending through the concaved portion 37, are designed to accommodate a flange 40 upon the adjacent end of the grate bar 23 in the manner as best illustrated in Figure 2 of the drawings. The innermost end of the longer ear 38 depends for an appreciable distance within the entrance to the ash pit 15 and is apertured to accommodate the adjacent offset end of a connecting rod 41. Said rod is likewise connected at its opposite end with an ear 42 depending from the under side of the circular grate 18.

From the foregoing description and accompanying drawings, it is obviously apparent that oscillatory movement may be imparted to the circular grate 18 when the grate shaker bar 33 is shifted toward and away from the furnace and the semi-circular grate members 25 and 26 respectively will be tilted upon the occasion across the face of the grate shaker bar being shifted laterally of the furnace. The flange 40 may be formed in any length to allow for appreciable outward and inward movement of the grate shaker bar whereby both forms of grates can be simultaneously operated by the one lever in a single operation when said bar is shifted obliquely across the face of the furnace.

The invention is susceptible of various changes in its form, proportions and minor details of construction, and the right is herein reserved to make such changes as properly fall within the scope of the appended claim.

Having thus described the invention, what is claimed is:—

A furnace construction comprising a ring provided with attaching ears secured to the inner surface of the furnace and subdividing same into a fire box and ash pit, bearing mem-

bers of arcuate formation carried by the ring and projecting within the enclosure defined thereby, a grate of circular formation slidably mounted upon the bearing members, said circular grate having a central opening, semi-circular grate members positioned within the central opening in the circular grate having journal portions projecting from the ends thereof, bearings arranged upon said ring to accommodate said journal portions, gear members carried by the journal portions and disposed for constant intermeshing engagement to facilitate simultaneous tilting and righting actions of the semi-circular grates, an operating lever mounted by a universal connection upon the furnace, ears carried by said lever and extending into the ash pit from the universal connection with the furnace, a connecting rod establishing connection between one of said ears and the circular grate, and a flange carried by and extending from one of the grate bars secured between said ears whereby simultaneous rotary oscillatory and tilting movements may be imparted to the circular and semi-circular grates respectively when the operating lever is shifted obliquely across the front of the furnace.

In testimony whereof I affix my signature.

HERBERT DREWS.
